UNITED STATES PATENT OFFICE.

HARVEY C. MASLAND, OF PHILADELPHIA, PENNSYLVANIA.

SURGICAL INSTRUMENT.

1,308,798.

Specification of Letters Patent.

Patented July 8, 1919.

Application filed June 24, 1918. Serial No. 241,475.

To all whom it may concern:

Be it known that I, HARVEY C. MASLAND, a citizen of the United States, residing in the city and county of Philadelphia, 5 State of Pennsylvania, have invented a new and useful Surgical Instrument, of which the following is a specification.

My invention consists of a surgical instrument adapted for drilling, burring, sawing, 10 doweling, etc., having variable gages and guards which may be adjusted with precision in a convenient manner.

It consists also of novel means on the grip part proper of the handle for stopping the 15 rotary motion of the tool when so required.

It consists also of a novel provision of the handle of the instrument whereby it may rest flat on a table or other support, and so be operated in a steady and stable manner.

20 The invention is satisfactorily illustrated in the accompanying drawing, but the important instrumentalities thereof may be varied, and so it is to be understood that the invention is not limited to the specific 25 details shown and described, as long as they are within the spirit or scope of the claims.

Figure 1 represents a perspective view of a surgical instrument embodying my invention.

30 Fig. 2 represents a transverse section on line 2—2 Fig. 1.

Fig. 3 represents a side elevation thereof.

Fig. 4 represents a partial side elevation, and a partial longitudinal section on line 35 4—4 Fig. 3.

Fig. 5 represents a longitudinal section similar to Fig. 4 with the handle resting on its flat side on a table or other proper support.

40 Fig. 6 represents a longitudinal section of a portion on line 6—6 Fig. 1.

Fig. 7 represents a section of a portion on line 7—7 Fig. 4.

45 Figs. 8 and 9 represent respectively different forms of surgical instruments that may be employed.

Fig. 10 represents a perspective view of a form of a guard for the bur shown in Fig. 8.

Fig. 11 represents a top or plan view of a 50 portion of a modification of the mechanism for stopping the rotation of the tool.

Fig. 12 represents a longitudinal section thereof on line 12—12 Fig. 11.

Similar numerals of reference indicate 55 corresponding parts in the figures.

Referring to the drawings:

1 designates the handle of the instrument adapted to be grasped in the operation of the same, it having mounted therein in the grip part proper thereof in the longitudinal direction thereof, the rotatable mandrel or shaft 2 to one end of which may be attached a flexible shaft or other means for communicating power to the mandrel, the other end of which is secured to the clutch 3 which 60 is adapted to have a drill, saw, bur, etc., fitted thereto and retained therein.

In the side of the handle is a longitudinally extending recess 4 which forms a runway for the plate 5 which is seated mov- 70 ably therein and provided with a longitudinally extending slot 6, the latter receiving the screw 7 which is adapted to enter the body of the handle, by which provision said plate may be adjusted forward or back- 75 ward on the handle and firmly held in position thereon.

The plate 5 has a portion 8 extended forward thereof and provided with side flanges, it occupying a position over the clutch 3 and 80 having seated on it the slidable arm 9 which is adjustable on said portion 8, the contiguous part of said arm 9 on said portion 8 within said side flanges having therein a slot 85 to receive the shank of the screw 10, which shank is connected with the said portion 8. On said shank is the nut 11 which when tightened is adapted to connect said arm 9 with said portion 8 and retain the former in adjusted position.

90 On the forward end of the arm 9 is the eye or segmental arch 12 which being tubular freely encircles the shank of the drill 13 and is adapted to form a depth gage for the latter, it being evident that by means of the plate 5, the extension 8 and the arm 9, the arch 12 may be adjusted with nicety and precision relatively to the work to be accomplished, it being noticed that the extension 8 and the arm 9 are of angular form so as 95 to be set properly over the clutch. As the eye or tubular arch is fitted over the drill or tool 13, it is centered on the latter and so stops true on the bone when the adjusted depth of penetration of the tool is reached, 100 and it serves also to protect soft tissues from being picked up and mutilated by the rotating tool. The arm 9 may have thereon a gage different from the gage 12, so said arm as differently equipped may be removed 105 110

from and reapplied to the plate 5 without displacing the latter from the handle or actually disturbing its adjustment thereon.

14, 15 and 16 represent side elevations of 5 other forms of tools or implements that may be employed in my invention.

In the handle 1 is a longitudinally extending bore 17 in which is freely fitted the slide- 10 able rod or pin 18 whose forward end is adapted to enter the recess 19 in the clutch 3 and act as a stop preventing rotation of the latter and consequently of the instrument thereon.

In order to withdrawn the pin from the 15 clutch, the rear portion thereof is provided with the stud 20 as a finger piece, and the handle has within it adjacent to the rear end of the bore 17, the elbow shaped recess 21 which when the pin 18 is withdrawn and 20 turned in proper direction is adapted to receive said stud 20, the forward wall 22 of the side wall 23 of said recess 21 then forming a shoulder which acts as a stop for said stud, it being noticed that the bottom of the 25 wall 21^x of said recess 21 opposite to the side wall 23 is cut away and inclined as in Fig. 2, so that the resilient device or spring 24 in the terminal portion of the bore 17 may push forward the pin 18 which carries said stud, 30 whereby the latter rides under the inclined bottom of the wall 21^x and is stopped against the forward wall 22 of the recess 21, as shown in Fig. 3, said recess when unoccupied by the stud 20 being shown in Fig. 6.

35 The nose or point of the pin is now held withdrawn from the recess 19 in the clutch 3 and the latter is free to be rotated.

By manipulating the stud it may be withdrawn from the wall 22, it moving under the 40 inclined bottom of the wall 21^x, after which it is turned in the recess 21 and out of the same when the spring 24 again becomes operative to advance the pin 18, and the nose or point of the latter enters the recess 19 of 45 the clutch, when the latter and consequently the tool is locked and prevented from rotation. In this case, the instrument is disconnected from the driving power when the instrument can be hand operated.

50 In certain cases for cutting from bone, cylindrical pins for doweling purposes it is important to support the handle 1 on a table or the like, while the instrument is in operation and so secure rigidity and stability, 55 hence the grip part of said handle has one portion of its surface, otherwise circular, cut-away forming the right-lined face 25 which may rest flat on said table, see Fig. 5.

In this case the plate 5 and the arm 9 with 60 the gage and guard 12 may be removed so as not to interfere with the movement of the handle, and consequently of the instrument.

In Fig. 10, the eye 12 is segmental or semi-tubular and is adapted to cover the bur 14 65 so that when the latter is in operation, said

eye protects the surrounding tissues without injuring the same.

In lieu of entering the pin 18 into the chuck 3 to prevent rotation thereof I form in the mandrel or shaft 2 the recess 26 which is adapted to receive the point of the pin 27, the latter freely occupying the handle 1 and having its head engaged by the forward end of the spring or spring plate 28 whose rear end is connected with said handle by the 75 screw 29, or other suitable fastening passing through said rear end into the handle 1. On the latter is the slide 30 which is adapted to ride forward over said spring 28 and de- 80 pressing the latter and the pin 27 causing the point of said pin to enter the recess 26 and so prevent rotation of the shaft 2, and consequently of the tool or implement on the clutch.

When the slide is pushed back, the spring 85 is free to rise when it raises the pin 27 and releases it from the shaft 2, whereby the latter is free to rotate and cause the operation of the chuck and tool or implement.

It will be seen that when the pin 18 is 90 engaged with the chuck, or the pin 27 is engaged with the driving shaft 2, the rotat- 95 ing mechanism is locked and becomes rigid with the handle, whereby the instrument may be used as a hand device independent of the driving motor.

It will be seen also that the means for ad- 100 justing the gage or guard for the tool are on the exterior of the handle and so con- 100 venient of access.

Having thus described my invention what I claim as new and desire to secure by Letters Patent, is:—

1. In a bone surgical instrument, a handle, a rotatable mandrel-like member mounted 105 thereon, means on said member adapted to connect it with and disconnect it from power driving mechanism, a tool carrier on said member, and means on said handle adapted to lock said carrier with the handle.

2. In a surgical instrument of the character stated, a handle, a rotatable tool carrying member mounted on said handle, a rotatable driving mandrel on said handle con- 115 nectible with said member, a gage for 115 said tool, and a support for said gage, said support being formed of a plurality of members which are adjustably connected with each other, and one of the members is adjustably connected with said handle.

3. In a surgical instrument of the character stated, a handle, a tool engaging chuck mounted on the latter, a driving member on said handle, and a pin-like member on said handle having one end adapted to be en- 125 gaged with said chuck to prevent rotation of the same and consequently of the tool, said pin-like member having thereon a fin- 130 ger piece which is adapted to rotate the lat- ter in opposite directions, said handle hav-

- ing therein a recess in which said piece is adapted to enter and engage with a wall of said recess as a stop for said pin-like member in the inoperative position of the same.
- 5 4. In a surgical instrument of the character stated, a handle, a tool carrying chuck-like member, a rotatable pin-like member on the handle with which said chuck-like member is connectible, a finger piece on said pin-like member adapted to rotate the latter and withdraw it from said chuck-like member, said handle having therein a recess in which said finger piece may engage when said pin-like member is withdrawn from said chuck-like member, and a resilient device on the handle adapted to bear against said pin-like member and force it toward said chuck-like member and retain it in engagement therewith, to hold said finger piece in engagement in said recess when said pin-like member is disengaged from said chuck-like member.
- 10 5. In a surgical instrument of the character stated, a handle, a tool engaging chuck mounted on the latter, a driving member on said handle, a pin-like member on said handle having one end adapted to be engaged with said chuck to prevent rotation of the same and consequently of the tool, said pin-like member having thereon a finger piece which is adapted to rotate the latter in opposite directions, said handle having therein a recess in which said piece is
- 15 adapted to enter and engage with a wall of said recess as a stop for said pin-like member in the inoperative position of the same, 35 and a resilient device adapted to bear against said pin-like member in the operative and inoperative positions of the latter.
6. In a surgical instrument of the character stated, a handle, a rotatable tool carrying member on the handle, a power driven mandrel on said handle adapted to be connected with said member, and a gage for the tool having a connection with said handle, said gage being of form adapted to surround the tool.
7. In a combined power and hand operated instrument, a handle, a rotating device mounted on said handle adapted to be 50 connected with power-driving mechanism, a tool carrier connectible with said device, and means on said handle adapted to lock said carrier and prevent free rotation of the same and of said tool, said handle having 55 on its side a flat surface adapting it to rest flat on a support whereby when said device is unlocked the handle may be held rigid on said support under the high speed rotation of the tool.
